UNITED STATES PATENT OFFICE.

CHARLES W. BINGEMAN, OF BUFFALO, NEW YORK.

DESIGN FOR A BADGE OR SIMILAR ARTICLE.

SPECIFICATION forming part of Design No. 30,556, dated April 18, 1899.

Application filed March 21, 1899. Serial No. 709,983. Term of patent 3½ years.

To all whom it may concern:

Be it known that I, CHARLES W. BINGEMAN, a citizen of the United States, residing at Buffalo, in the county of Erie and State of New York, have invented and produced a new and original Design for a Badge or Similar Article, of which the following is a specification, reference being had to the accompanying drawing, forming a part thereof.

This design relates to the ornamentation of a badge or similar article, the same being shown in the accompanying drawing, which shows a face view of my design.

The leading feature of my design consists of the representation of a buffalo and the figure of an Indian holding a pan below the head of the buffalo.

Referring to the drawing, A represents the figure of a buffalo, B the figure of an Indian, and C the pan, which is held in one hand of the Indian below the head of the buffalo. D represents a flag arranged in the other hand of the Indian.

What I claim is—

The design for a badge or similar article, substantially as herein shown and described.

Witness my hand this 15th day of March, 1899.

CHARLES W. BINGEMAN.
